EVAPORATOR

Martin J. Kerner, Buffalo, N. Y., assignor to
Buffalo Foundry & Machine Co., Buffalo, N. Y.,
a corporation of New York

Application October 6, 1933, Serial No. 692,517

12 Claims. (Cl. 159—28)

This invention relates to an evaporator which is more particularly intended for eliminating excess moisture from solutions of a corrosive character which cannot be treated in an apparatus made of materials which would be attacked by the solute of the solution. For example, a liquor such as sulphuric acid which is used in the process of making artificial silk and from which excessive moisture must be removed in order to offset the dilution during the process and restore the strength of the acid and permit of using the same repeatedly, cannot be treated in an apparatus having steel or similar metal which is exposed to the acid.

It has therefore been the custom to so construct evaporators for treating solutions containing sulphuric acid that all surfaces exposed to the acid or corrosive liquid are made of lead or other non-corrosive material which is not affected by the same. In such prior structures the solution contacted with the outer side of a plurality of tubes or flues of lead or the like while steam was passed through the inner side of the tubes, and the tubes were supported at their ends on sheets or plates of steel or iron having their inner surfaces coated with lead or the like which was burned on the flue plates or sheets.

Heretofore it was the custom to burn the coatings of lead on to the inner surface of the supporting steel plate so as to form a non-corrosive lining on the latter, which was not satisfactory inasmuch as this procedure was not only very expensive due to the slowness of the process, but also because of the uncertainty of fully lining or facing the steel with lead, owing to the possibility of leaving small holes, openings or crevices in the layer of lead at different places through which acid could work its way and attack the supporting steel plate.

It is the object of this invention to provide an evaporator for eliminating moisture from corrosive liquors which so mounts the lead or non-corrosive linings or facings on the steel or corrosive supporting plates that these linings completely cover all parts of the supporting plates and are securely connected therewith and reliably support the tubes and thereby render the apparatus strong and durable and avoid the necessity of frequent attention or repairing.

In the accompanying drawings:

Figure 1 is a vertical section, on a reduced scale, of an evaporator embodying a practical form of my invention.

Figure 2 is a horizontal section of the same, taken on line 2—2 Fig. 1.

Figure 3 is an elevation of one of the headers for supporting an end of the tubes or flues.

Figure 4 is a fragmentary vertical longitudinal section, on an enlarged scale, of one of the headers, manifold chambers, and the adjacent part of the evaporator body.

Figure 5 is a fragmentary vertical transverse section, on an enlarged scale, taken on line 5—5 Fig. 1, and looking inwardly.

Figure 6 is a fragmentary vertical section, on an enlarged scale, taken on line 6—6 Fig. 5, and showing one form of packing suitable for forming a tight joint between an end of each evaporating tube and a tube header or support.

Figure 7 is a cross section taken on line 7—7 Fig. 6.

Figure 8 is a vertical section similar to Fig. 6, showing a modified form of the packing for the joint between each evaporating tube and the header of a manifold chamber.

Figures 9, 10 and 11 are fragmentary vertical sections showing the method of procedure in mounting a previously prepared non-corrosive sheet or plate on the inner side of one of the supporting plates of a header forming part of a manifold of the evaporator.

In the following description similar characters of reference indicate like parts in the several figures of the drawings.

The body of this evaporator which forms the evaporating chamber or tank 10 adapted to receive the liquor to be evaporated, has all of its parts which come in contact with the solution, made of a corrosive-resistant material, such as lead if the solute in the solution is sulphuric acid, and in the form of this body as shown in Figs. 1 and 2, the same comprises an upright cylindrical side wall 11, a downwardly tapering or conical bottom 12 and an upwardly dished top 13. The liquor to be treated may be introduced into the evaporating chamber in any suitable manner, as for example through an inlet 14 in the central part of the side wall, and the liquor may be withdrawn through a discharge 15 adjacent to the lower end of the conical bottom. The vapors produced in the evaporating chamber due to heating the liquor therein are drawn off through a vapor outlet 16 in the top of the evaporator body by any suitable exhausting means so as to create a vacuum in the evaporating chamber, whereby the solution in the evaporating chamber is concentrated and in some cases salts or crystals are precipitated during the process of evaporation.

The means for heating the liquor in the evap-

orating chamber which embody the present improvements are constructed as follows:

The numeral 17 represents a plurality of heating tubes, pipes or flues which are made of lead or other corrosive resistant metal or material and which are arranged horizontally and extend transversely across the space within the lower part of the evaporating chamber so as to be submerged in the liquor therein. These heating tubes are heated by means of steam or other heating medium supplied to the interior of the same, which heat is transferred to the liquor by contact with the exterior of the heating tubes, thus vaporizing the water in the liquor and concentrating the liquor and in some instances producing salts or crystals.

Inasmuch as the heating tubes when made of lead for use in concentrating diluted sulphuric acid are comparatively weak and liable to become distorted, particularly when of considerable length, due to the weight of the material and the absence of rigidity in the same, means are provided for supporting these tubes and maintaining them constantly in the proper normal condition. The preferred means for accomplishing this purpose consist in placing a supporting tube or tubular core 18 of steel or the like in each heating tube so that the periphery of the supporting tube fits closely against the bore of the respective heating tube, thereby preventing the latter from being distorted by any pressure which is exerted against the outer side of the same. For the purpose of increasing the heating effect of the steam on the heating tube the supporting tubes are provided with a plurality of holes 19 which are suitably distributed throughout the length of each supporting tube so as to permit the heating medium to contact directly with the heating tube at a plurality of separated areas and thereby increase the heat transference and still maintain a reliable support for the lead heating tubes.

Although various means may be employed for supplying a heating medium, such as steam, to the heating tubes and discharging the water of condensation of the spent steam it is preferable to utilize for this purpose the means which are constructed in accordance with this invention as follows:

The numeral 20 represents a heating medium inlet manifold chamber which communicates with one end of the several heating tubes, and 21 a heating medium outlet manifold chamber which communicates with the opposite ends of the heating tubes. Inasmuch as these manifold chambers are of substantially the same construction the following description of one applies to both so far as corresponding parts are concerned.

Each of these manifold chambers includes an upright inner tube plate, sheet or header 22, an outer upright cover plate or wall 23 and a horizontal tubular side wall 24 arranged between the inner and outer plates 22, 23.

For securing greater strength and also economy the side wall of each manifold chamber is preferably constructed of cast iron and the corresponding inner and outer plates are constructed of sheet steel. These manifold chambers are arranged externally of the evaporating chamber and opposite openings 25, 26 on diametrically opposite sides of the upright wall of the evaporating chamber through which the ends of the heating tube project. On its exterior the evaporating chamber is provided with a horizontal collar 35 around each of said openings 25, 26.

The marginal part of the tube plate of each manifold chamber 24 is arranged between the inner end of the respective manifold side wall and the outer end of the respective collar 35 of the evaporator body side wall and secured to these parts by means of bolts 27 passing through the marginal parts of this tube plate and flanges 28, 29 formed respectively on the outer end of said collar and the inner end of this manifold side wall, as shown in Fig. 4. The outer cover plate 23 of each manifold chamber is connected with the outer end of the respective side wall 24 by bolts 30 or other suitable means. The inlet manifold is provided in its top with an inlet 31 for steam when this medium is used for heating the liquor to be concentrated, and each of the manifold chambers is provided at its bottom with an outlet 32 through which water of condensation is removed from the manifold chambers and the heating tubes communicating therewith.

Each of the tube plates is provided with a plurality of tube openings 33 through each of which one end of a heating tube and its supporting tube projects from the evaporating chamber into one of the manifold chambers. For the purpose of protecting the steel tube sheets of the manifold chambers against corrosion by the liquor which is being concentrated and also to form a leak-tight joint between each heating tube and the tube plates, the following means are provided.

The numeral 34 represents a protecting plate, lining, facing or covering of lead or other corrosion resistant metal or material which extends over the entire surface of that part of the inner side of each tube plate which is within the respective collar 35 of the evaporator body and thus protects the same against attack by the corrosive liquors which are being evaporated, such as diluted sulphuric acid. This protecting covering comprises a previously prepared plate 40 which is provided with a plurality of integral bushings, collars, or tubular nipples 36 each of which is formed integrally with the respective non-corrosive plate and projects outwardly therefrom and into one of the tube openings 33 of the respective tube sheet. Each of these tube openings is provided adjacent to its inner end with an internal outwardly facing shoulder which may be either at right angles to the axis of this opening, as shown at 37 in Figs. 4 and 6, or the same may be of outwardly flaring or conically enlarging form, as shown at 38 in Fig. 8. In the construction shown in Figs. 4 and 6 the outer end of each bushing or nipple 36 is provided with an external flange 39 which is integral with the respective bushing and bent at right angles to the axis of the same and into engagement with the shoulder 37, thereby securely interlocking the respective tube sheet and corrosive resistant covering and holding the same tightly together in an assembled position.

Each of the heating tubes passes at its opposite ends through the corresponding bushings or nipples of the corrosive resistant coverings of the respective manifold chamber tube sheets and fits these bushings fairly tight, but to ensure against leakage through the joints between the heating tubes and the corrosive resistant coverings from the evaporating chamber to the manifold chambers packing means are provided which, in the form shown in Fig. 6, are constructed as follows:

The numeral 40 represents a packing ring or gasket of corrosive resistant material such as blue asbestos and graphite, surrounding the lead tube 17 at the outer end of the respective bushing 36.

and its flange 39, 41, an intermediate follower ring 40 of metal surrounding the respective tube at the outer end of the gasket 40, 42, an outer clamping gland having a screw connection with the outer end of the respective tube opening 33 in the tube plate, and 43 represents a washer of bronze interposed between the inner end of the gland and the outer end of said follower ring.

The packing ring 40 has a flat inner bearing face 44 which is arranged at right angles to the axis of this ring and the opening 33 and engages with the corresponding outer face of the flange 41 on the adjacent bushing 36 and also has an external conical wedge face 45 which tapers from the large inner end of this ring toward the small outer end of the same. The follower ring 41 has an inwardly flaring conical bore 46 which has a wedging engagement with the conical face 45 of the packing ring. The opposite sides of the bronze washer 43 and the opposing outer and inner faces 47, 48 of the follower ring 41 and the gland 42 engaging with the opposite sides of the washer are arranged at right angles to the axis of the respective heating tube. Upon tightening the gland 42 the follower ring 41 is pushed inwardly and the latter not only pushes the packing ring lengthwise against the bushing flange 39 but also contracts the packing ring around the heating tube due to the co-operating inclined surfaces 45, 46 on these members, thereby forming a liquid-tight joint between the non-corrosive heating tube and the non-corrosive covering 34 of the respective tube sheet and confining the corrosive liquor within the evaporating chamber and preventing the same from attacking any corrodible metal parts of the manifold chambers.

If desired, the joint between the heating tubes and the corrosive resistant covering of the tube sheets may be sealed by the means shown in Fig. 8, in which case the flange 49 on the outer end of each bushing 36 is of outwardly flaring form and engages its conical outer side 491 with the outwardly flaring shoulder 38 of the respective opening in the tube plate. In this modified form a packing ring or gasket 50 is employed which has an inwardly tapering inner end 51 engaging with the conical inner side 492 of the flaring flange 49, and an outwardly dished bronze washer 52 is employed which engages its conical inner side with the outwardly tapering end 53 of the packing ring, while its conical outer side engages with the inwardly flaring conical face 54 on the inner end of a gland 55 which is connected by a screw joint with the outer end of the tube opening 33 in the respective tube plate.

After the tube plates have been assembled with the body of the evaporator the edges of the lead coverings on the inner side of the tube plates are burned to the lead body of the evaporator, as shown at 56 in Figs. 1 and 4, so as to effectually guard against leakage through the joints at these places.

By these means the corrosive liquor can only come in contact with lead which is pure and all liability of this liquor seeping through the coverings of the tube plates is prevented, thus ensuring operation of the evaporator without the necessity of frequent repairing as has been the case in evaporators of this type as heretofore constructed.

In the process of making and applying each protecting covering to the respective tube supporting plate of each header a plate or sheet of lead is first provided by punching, drilling or otherwise with a small hole 60, as shown in Fig.

9, which is located to correspond with the axis of one of the tube openings 33 in the tube supporting sheet. The area of the metal surrounding each of these small holes is then swaged outwardly by suitable means so as to form integrally thereon an outwardly projecting tubular nipple, collar or bushing 36 which is cylindrical throughout its length, as shown in Fig. 10. This protecting plate is then placed against the inner side of the supporting plate 22 with each of its bushings or nipples 36 projecting outwardly through one of the openings 33 in the supporting plate, as shown in Fig. 11. The outer end of each bushing 36 is then swaged or upset so as to form the laterally projecting flange 39 and engage the latter firmly with the outwardly facing shoulder 37 on the opening 33 of the supporting plate, as shown in Figs. 4 and 6. Thereafter the supporting plate 22 is assembled with the tubes, packings and other parts of the evaporator to produce the completed structure shown in Figs. 1 and 2.

I claim as my invention:

1. An evaporator comprising an evaporating chamber having a wall which includes a supporting plate of corrodible material provided with a plurality of openings, a protecting plate of non-corrodible material engaging the inner side of said supporting plate and provided with a plurality of outwardly projecting tubular bushings each of which is arranged in one of the openings of said supporting plate, and a plurality of tubes of corrosive resistant material each of which is arranged in a bushing of said protecting plate.

2. An evaporator comprising an evaporating chamber having a wall which includes a supporting plate of corrodible material provided with a plurality of openings, and an outwardly facing internal shoulder in each of said openings, a protecting plate of non-corrodible material engaging the inner side of said supporting plate and provided with a plurality of outwardly projecting tubular bushings each of which is arranged in one of the openings of said supporting plate and provided with a laterally projecting flange which engages with the outwardly facing shoulder in the respective opening of the supporting plate, and a plurality of tubes of non-corrodible material each arranged in one of the bushings of said protecting plate.

3. An evaporator comprising an evaporating chamber adapted to contain the solution to be evaporated, tube plates arranged at opposite sides of said chamber and each provided with a plurality of tube openings, a non-corrodible lining arranged on the inner side of each tube plate and having a plurality of tubular bushings each of which projects outwardly into one of the openings in one of said tube plates, and a plurality of heating tubes arranged in said chamber and adapted to receive a heating medium, and each having its ends arranged in corresponding bushings of said linings.

4. An evaporator comprising an evaporating chamber adapted to contain the solution to be evaporated, tube plates arranged at opposite sides of said chamber and each provided with a plurality of tube openings, a non-corrodible lining arranged on the inner side of each tube plate and having a plurality of tubular bushings each of which projects outwardly into one of the openings in one of said tube plates, and a plurality of heating tubes arranged in said chamber and adapted to receive a heating medium, and each having its ends arranged in corresponding bushings of said linings.

ings of said linings, and inlet and outlet manifold chambers for the heating medium communicating with opposite ends of said tubes.

5. An evaporator comprising an evaporating chamber adapted to contain the solution to be evaporated, tube plates arranged at opposite sides of said chamber and each provided with a plurality of tube openings, and an internal outwardly facing shoulder in each of said openings, a non-corrodible lining arranged on the inner side of each of said tube plates and provided with a plurality of integral bushings each of which projects outwardly into one of said tube openings and is provided at its outer end with a laterally projecting flange which engages with the outwardly facing shoulder in the respective tube opening, and a plurality of non-corrodible heating tubes arranged in said evaporating chamber and each having its opposite ends arranged in corresponding bushings of the linings on said tube plates.

6. An evaporator comprising an evaporating chamber adapted to contain the solution to be evaporated, tube plates arranged at opposite sides of said chamber and each provided with a plurality of tube openings, a non-corrodible lining arranged on the inner side of each tube plate and having a plurality of tubular bushings each of which projects outwardly into one of the openings in one of said tube plates, and a plurality of heating tubes arranged in said chamber and adapted to receive a heating medium and each having its ends arranged in corresponding bushings of said linings, and packing means arranged in the outer part of each of said tube openings around the heating tube therein and engaging with the bushing of the lining of the respective tube plate.

7. An evaporator comprising an evaporating chamber adapted to contain the solution to be evaporated, tube plates arranged at opposite sides of said chamber and each provided with a plurality of tube openings, and an internal outwardly facing shoulder in each of said openings, a non-corrodible lining arranged on the inner side of each said tube plates and provided with a plurality of integral bushings each of which projects outwardly into one of said tube openings and is provided at its outer end with a laterally projecting flange which engages with the outwardly facing shoulder in the respective tube opening, a plurality of non-corrodible heating tubes arranged in said evaporating chamber and each having its opposite ends arranged in corresponding bushings of the linings on said tube plates, and packing means arranged in the outer part of each of said tube openings around the heating tube therein and engaging with the flange of the respective bushing.

8. An evaporator comprising an evaporating chamber adapted to contain the solution to be evaporated, tube plates arranged at opposite sides of said chamber and each provided with a plurality of tube openings, and an internal outwardly facing shoulder in each of said openings, a non-corrodible lining arranged on the inner side of each of said tube plates and provided with a plurality of integral bushings each of which projects outwardly into one of said tube openings and is provided at its outer end with a laterally projecting flange which engages with the outwardly facing shoulder in the respective tube opening, a plurality of non-corrodible heating tubes arranged in said evaporating chamber and each having its opposite ends arranged in corre-

sponding bushings of the linings on said tube plates, a packing surrounding each of said heating tubes within one of said tube openings and bearing against the outer side of the flange of the respective bushing, and a gland screwed into the outer end of each tube opening and engaging its inner end with the outer end of the respective packing.

9. An evaporator comprising an evaporating chamber adapted to contain the solution to be evaporated, tube plates arranged at opposite sides of said chamber and each provided with a plurality of tube openings, and an internal outwardly facing shoulder in each of said openings, a non-corrodible lining arranged on the inner side of each of said tube plates and provided with a plurality of integral bushings, each of which projects outwardly into one of said tube openings and is provided at its outer end with a laterally projecting flange which engages with the outwardly facing shoulder in the respective tube opening, a plurality of non-corrodible heating tubes arranged in said evaporating chamber and each having its opposite ends arranged in corresponding bushings of the linings on said tube plates, a packing surrounding each of said heating tubes within one of said tube openings and bearing against the outer side of the flange of the respective bushing, and a gland screwed into the outer end of each tube opening and engaging its inner end with the outer end of the respective packing, said flange having an outwardly flaring face, said gland having an inwardly flaring face, and said packing having its inner and outer ends tapered to correspond to the flaring faces of said flange and gland.

10. An evaporator comprising an evaporating chamber adapted to contain the solution to be evaporated, tube plates arranged at opposite sides of said chamber and each provided with a plurality of tube openings, a non-corrodible lining arranged on the inner side of each tube plate and having a plurality of tubular bushings, each of which projects outwardly into one of the openings in one of said tube plates, a plurality of heating tubes arranged in said chamber and adapted to receive a heating medium, and each having its ends arranged in corresponding bushings of said linings, and packing means arranged in the outer part of each of said tube openings around the heating tubes therein and engaging with the bushing of the lining of the respective tube plate, and including an inner packing ring having a flat transverse inner face engaging the outer side of the respective bushing flange and a tapering outer end, an intermediate follower ring having a flaring inner face engaging with the tapering outer end of said packing ring, a gland having a screw connection with the outer end of said tube opening, and a washer interposed between said gland and follower ring.

11. The herein-described method of mounting a protecting plate on a supporting plate for use in a tubular evaporator which consists in providing a supporting plate with relatively large openings, and annular outwardly facing shoulders around said openings, forming small holes in the said protecting plate corresponding to said openings, swaging the material of said protecting plate around each of said holes to form integral bushings thereon, assembling said plates so that they engage each other and the bushings of the protecting plate project into the openings of the supporting plate, and bending the outer end of

the bushing in each opening to form an annular flange which engages the shoulder thereof.

12. An evaporator including a chamber having a wall comprising a supporting sheet of corrodible material provided with a plurality of openings and a protecting sheet of non-corrodible material engaging with one side of said supporting

sheet and having a plurality of integral tubular bushings each of which projects into one of said openings of the supporting sheet, and a plurality of tubes of non-corrodible material arranged in said bushings.

MARTIN J. KERMER.
